UNITED STATES PATENT OFFICE.

GEORGE R. BOYD, OF CAIRO, ILLINOIS.

DESIGN FOR A SIDING-BOARD.

SPECIFICATION forming part of Design No. 23,106, dated March 6, 1894.

Application filed November 28, 1893. Serial No. 492,301. Term of patent 7 years.

To all whom it may concern:

Be it known that I, GEORGE R. BOYD, a citizen of the United States, residing at Cairo, in the county of Alexander and State of Illinois, have invented and produced a new and original Design for Siding-Boards, of which the following is a specification.

Reference is to be had to the accompanying drawing forming a part of this specification, in which similar letters of reference indicate corresponding parts.

The figure is a broken perspective view of a board embodying my new design.

The leading feature of my design consists in the novel shape, shown to-wit: the lines of

the inner and outer surfaces, *a*, *b*, at an angle to each other, the thicker end of the board having a rabbet-like recess *c* at the inner angle and the bottom wall *d* of such recess being in a plane which is at an angle to the inner surface *a* and substantially parallel with the plane of the outer surface *b*, and the ogee *e* at the thicker end, at the outer angle thereof. 20

I claim—

The design for a siding board herein shown 25 and described.

GEORGE R. BOYD.
